US Trademark Application #86755435 (now Registered Trademark #4945782) for "Sohoodie," filed Sep. 14, 2015 by SoHoodie LLC. First Use in Commerce Date: Jul. 1, 2015. Retrieved on Jun. 16, 2018. (Year 2015).*

Primary Examiner — Karen S Acker*Assistant Examiner* — Jasmine Mlinarcik(74) *Attorney, Agent, or Firm* — The Law Firm of Andrea Hence Evans, LLC(57) **CLAIM**

The ornamental design for a portable hood, as shown and described.

DESCRIPTION

FIG. 1 is a left side perspective view of a portable hood; FIG. 2 is a right side perspective view thereof; FIG. 3 is a front perspective view thereof; FIG. 4 is a rear perspective view thereof; FIG. 5 is a right side view thereof; FIG. 6 is a left side view thereof; FIG. 7 is a top view thereof; and, FIG. 8 is a bottom view of the invention. The features of the portable hood drawn in broken lines depict environmental structure that forms no part of the claimed design.
